Application June 10, 1935, Serial No. 25,783

5 Claims. (Cl. 113—38)

This invention relates in general to power presses and more particularly to the type of press in which there is employed a plurality of reciprocable die carrying slides.

Heretofore in presses of this character the movements of the slides with respect to each other in each cycle of operation of the press, have been fixed, so that after one slide has moved a predetermined distance, on the operative stroke, the second slide would commence its movement, and on the return stroke the movements of the slides with relation to each other are also fixed. Such movements, as well as the order of movement of the slides with respect to each other could not be changed or varied.

It is one of the objects of the present invention to provide in a press of this character improved means whereby the movement of each slide may be controlled independently with respect to each other, and the time and order of operation of one slide with relation to the other may be selectively controlled or determined, according to the nature of the work being operated upon, and at the will of the operator.

It is also important that means should be provided to arrest the movement of the slide or slides at any predetermined point in the cycle of its operation, and that this point of arrest in the movement of the slide be accurately repeated upon each stroke of the press, for any desired number of strokes without any appreciable variations in such point of arrest.

Heretofore in the operation of presses of this character, and by reason of inaccuracies caused by the stopping mechanism, such as slippage of the braking means, overthrow of the driving mechanism for the slides, or for various reasons, it is not always possible to arrest the movement of the slide at the limit of its throw, with the result that there will be a slight movement of the slide away from the work, or the slide may be arrested before it reaches the limit of its stroke, which conditions are undesirable, and in many instances disastrous with respect to the work being operated upon.

It is therefore another object of the present invention to provide in a press of this character improved means for minimizing the inaccuracies of the stopping or the arresting of the slide at the limit of the stroke, or at a predetermined point, by reason of the slippage of the braking means, overthrow of the slide actuating means, or for various other reasons. This may be accomplished by means of linkage mechanism forming opera-

tive connections between the slides and the respective slide driving or operating mechanism. These links are so designed and arranged, that if there should be a considerable overthrow or underthrow of the operating or power means, any motion of the slide by reason of such overthrow or underthrow at the desired stopping point or limit of the stroke, will be only a small fraction in the up and down movement of the slide, as compared with the movement of the driving means, and which fraction of movement will not be sufficient to appreciably affect the gripping or holding action upon the work, of the die carried by the slide.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating the invention in connection with a press in which there is provided a plurality of reciprocable die carrying slides, and in which drawings

Figure 1 is a view partly in elevation, partly in section, partly broken away, and with parts omitted, of a press of this character constructed in accordance with the principles of this invention, and as taken on line 1—1, Figure 2.

Figure 2 is a vertical, sectional view as taken on line 2—2, Figure 1.

Figures 3, 4 and 5 are diagrammatic views showing one of the slides, the operating mechanism therefor, and the position the slide will assume at different points in the cycle of operation of the same.

Figure 6 is an enlarged detail sectional view of a form of clutch mechanism.

Figure 7 is a wiring diagram.

Figure 8 is a view partly in elevation, partly in section and partly broken away, of one of the controls for one of the clutches.

Figure 9 is an enlarged detail sectional view taken on line 9—9, Figure 8.

Figure 10 is a view similar to Figure 1 of another form of press.

Referring more particularly to the drawings the numeral 10 designates generally the frame of a press which is provided with uprights 11 upon which one of the slides operates.

The uprights are connected at the top in any suitable manner, here shown as being by means of a hollow crown 12, and at the bottom of the

press frame is arranged a bed 13 upon which latter a die 14 may be mounted.

Reciprocable upon suitable guides 15 carried by the uprights 11 is a slide 16, to which a die

5 17 is connected. The slide 16 is adapted to be given a reciprocatory movement preferably in the following manner. A shaft 18 is supported in suitable bearings 19 in the press frame, and which shaft may also extend through bearings in intermediate partitions or uprights 20 in the crown.

10 Supported by the shaft 18 and preferably adjacent each end of the shaft are opposed eccentrics 21-22, one pair of the eccentrics being provided for each end of the slide 16. Eccentric straps 23-24 respectively co-operate with the eccentrics 21-22, and these straps are also respectively provided with arms 25-26 of any desired or suitable length.

15 Levers 27, preferably of the bell crank type, are pivotally mounted as at 28 on each side of the shaft 18, one arm 29 of the lever being pivotally connected as at 32 with one end of a link 33, of any desired or suitable length, and the other end of each of the links 33 is pivotally connected as at 34 to anchoring devices 35 which are adjustably connected to the ends of the slide 16. Any suitable fastening means for the anchoring device may be provided, and to that end the anchoring device may be screw threaded to pass 20 through portions 36 of the slide, and nuts or collars 37 may be provided on the threaded portion of the anchoring device for securing the anchoring device and the slide adjustably together. One set of these eccentric and link connections is arranged at each end of the slide 16.

25 The bell crank levers 27 are adapted to be oscillated about their pivots 28, and to that end the pivots 28 may be formed by a shaft connecting the co-operating levers or the levers may 30 oscillate about the shaft.

35 Each of the eccentrics 22 at each end of the outer slide is connected with a gear 38 for rotation therewith, and these gears are mounted to rotate about the shaft 18.

40 Each of the eccentrics 21 at the end of the slides is connected for rotation with a gear 38^a, and these gears also are supported by and are rotatable about the shaft 18.

45 The gears 38 rotate in one direction as indicated by the arrow in Figure 2, and the gears 38^a rotate in the opposite direction, causing the respective eccentrics 21-22 to rotate in the directions indicated by the arrows in Figure 1. The gears 38 are rotated by means of pinions 39 50 meshing therewith and secured to a shaft 40 for rotation with the shaft, while the gears 38^a are rotated by means of pinions 39^a meshing therewith and secured to a shaft 43 for rotation therewith.

55 60 All of the gears and the eccentrics thus far described are preferably located within the hollow crown of the press.

65 The shafts 40 and 43 are connected together by means of intermeshing gears 44-45, and to one of the shafts 40-43 is secured a drive pulley 41 over which a driving belt 42 passes. The pulley constitutes the portion of a clutch mechanism to be hereinafter described. The belt receives its motion from any suitable source of 70 power so that, under certain conditions, to be hereinafter described, when the shafts 40-43 are rotated by the pulley 41, the gears 38 and 38^a together with the eccentrics connected thereto, will be rotated about the shaft 18, causing a 75 reciprocation of the slide 16.

In the present form of the invention there is shown a second slide 46 (see Figure 2) which is reciprocable within the slide 16 and is adapted to carry a die 47 which is secured thereto.

This inner slide 46 is also reciprocable by means of eccentrics 48-49 arranged adjacent each end of the inner slide and preferably intermediate the innermost eccentrics 21-22. The eccentrics 48-49 adjacent each end of the inner slide are opposed to each other and are rotated about the 10 shaft 18, eccentric straps 50-51 co-operating with the respective eccentrics. These straps are respectively provided with arms 52, similar to the arms 25-26, to each of which arms one end of a lever 53 is pivotally connected as at 54, the 15 lever being mounted to oscillate about the pivot 28. The other end of each of the levers 53 is pivotally connected as at 55 to a link 56, and the other end of each of the links 56 is pivotally connected as at 57 to an anchor device 58, each 20 of which is adjustably secured to the inner slide 46. To that end the anchor device may be threaded so as to pass through suitable projections or bearings in the slide 46, and nuts or collars 59 may be provided to secure such ad- 25 justment.

The lever 53 may be provided with a tubular extension 60 journaled upon the shaft 18, and carrying arms 61 to which one end of one of the links 56 is pivotally connected as at 62, and the other end of the link 56 is pivotally connected as at 63 to an anchoring device 64 that is adjustably secured to the slide 46. When the levers 53 are rocked about the pivot 28, the arms 61 will co-operate with the lever 53 to assist in 35 reciprocating the slide 46.

The eccentrics 48 and 49 are respectively secured to gears 65-66, and the eccentrics are disposed in opposite directions with respect to each other. The gears 65-66 are rotatable 40 about the shaft 18, and to that end there is provided a shaft 67 journaled in suitable bearings, and to which shaft is connected a pinion 68 which meshes with the gear 65.

A shaft 69 journaled in suitable bearings has 45 secured to it a pinion 70 which meshes with the gear 66, and these two shafts 67-69 are connected together by intermeshing gears 71-72, respectively secured thereto, and to one of which gears 71-72, a clutch member 73, to be hereinafter more fully described, is secured. When the clutch 73 is rendered active in a manner to be described, the gears 65-66 will be rotated in the directions indicated by the arrows in Figure 2, and this will cause the inner slide to be recip- 50 roated.

Beneath the bed 13 of the press is arranged a slide 74 carrying a die 75 which, in the present form of the invention operates through the bed of the press and also within the die 14, and co- 60 operates with the die 47 on the inner slide 46, to shape the work 76, the die 17 on the outer slide 16 also co-operating with the die 14 to hold the work 76 while it is being operated upon.

This lower slide 74 is operated in a manner 65 similar to the other slides of the press, and to that end there is provided a suitable shaft 77 mounted in suitable bearings below the bed of the press, and rotatable about the shaft 77 are gears 78-79. To the gear 78 there is secured an ec- 70 centric 80 with which an eccentric strap 81 co-operates, and this strap is provided with an arm 82 to which one end 83 of a bell crank lever 84 is pivotally connected as at 85, the lever 84 being oscillatable about a pivot 86. The other 75

5 arm 87 of the bell crank lever is pivotally connected as at 88 to one end of a link 89, and the other end of the link 89 is pivotally connected as at 90 to a securing device 91 which is adjustably connected to the slide 74. To the gear 79 is secured an eccentric 92 for rotation therewith, and these gears 78—79 and eccentrics 80 and 81 are rotatable about the shaft 77.

10 The eccentrics 80 and 92 are disposed in opposite directions from each other, and an eccentric strap 93 co-operates with the eccentric 92 and is provided with an arm 94. The arm 94 is pivotally connected as at 95 to the arm 96 of a bell crank lever 97 oscillatable about a pivot 98. The other end arm 99 of the bell crank lever is pivotally connected as at 100 to a link 101. The free end of the link is pivotally connected as at 102 to a fastening or anchoring device 103 adjustably secured to the slide 74.

15 20 The gears 78 and 79 are adapted to be rotated in the following manner.

25 A pinion gear 104 is secured to a shaft 105 for rotation therewith and which shaft is journaled in suitable bearings. A pinion 106 is secured to a shaft 107 for rotation therewith, and the shafts 105 and 107 are connected together for simultaneous rotation by means of intermeshing gears 108—109. One of the shafts 105—107 is connected to the shaft of a clutch member 110 which, when the latter is rotated in a manner to be described, will cause a reciprocation of the slide 74 and the eccentrics 80 and 92 rotate in the opposite direction so as to effect a proper movement of the slide.

30 35 Obviously, the operating mechanism for each of the slides is the same at both ends of the slide.

40 There is shown in Figure 6 of the drawings a form of clutch mechanism, and as the mechanism is similar in the clutches 41, 73 and 110, a specific description of one will apply to each of the clutches. The particular clutch shown is designated by the reference character 12 in Figure 2.

45 The clutch element 111 is secured to the shaft 67 for rotation therewith and is preferably connected to the shaft by means of a key connection 112 adapting the element to be moved lengthwise of the axis of the shaft. A spring 113 operates upon the clutch element and tends normally to move it in one direction with respect to the co-operating clutch element 73.

50 55 A magnet or electro-responsive device 114 is provided for operating the clutch element 111, and co-operating with the magnet is an armature or solenoid 115, having connection by means of a suitable yoke 116 with the clutch element 111.

60 When the magnet 114 is energized, the clutch element 111 will be moved against the stress of the spring 113 to effect an operative connection between the clutch element 111 and the shaft 67 so as to cause the clutch element 73 to be rotated with the shaft. When the magnet 114 is de-energized, the spring 113 will move the clutch element 111 into an inactive position with respect to the element 73, and the clutch element 73 will then be adapted to rotate independently with respect to the clutch element 111.

65 70 Connected to the clutch element 73 for rotation therewith are gears 117—118—119, and over the gear 117 a sprocket chain 120 passes, and this sprocket chain also passes over a sprocket wheel 121 connected with the clutch element 41 which is mounted upon the shaft 43 for rotation thereabout, so that when the clutch element 41 is rotated, its motion will be transmitted through the 75 sprocket chain 120 to the clutch element 73

which rotates freely upon the shaft 67. The clutch element 41 is mounted loosely upon its supporting shaft so as to continuously rotate but when the clutch element 41 is secured to the co-operating clutch element, the shafts 43 and 40 will be rotated. Passing over the sprocket wheel 118 which is secured to the freely rotatable element 73 of the clutch, is a sprocket chain 122 which also passes over a sprocket wheel 123 on the freely rotatable element 124 of the clutch 10 device 110 that controls the movement of the lower slide 74, the clutch device 73 controlling the rotation of the shafts 67 and 69 that rotate the gears 65 and 66 that control the operation of the inner upper slide 46.

15 It will thus be seen that there is provided a clutch device for controlling the operation of the outer upper slide 16, a clutch device for controlling the operation of the inner upper slide 46, and a clutch device for controlling the operation of the lower slide 74, all of which are operatively connected and which devices are adapted to be selectively controlled in a manner to be described so as to vary or alter not only the time of operation of the respective slides in the cycle 25 of operation of the machine, but to vary or alter the relative time of operation of these slides one with respect to the other.

20 It will therefore be manifest that in order to selectively control the operation of the slides, it 30 is only necessary to selectively control the clutch devices on the respective operating shafts for the slides.

25 Any suitable means may be provided for that purpose, but in the present exemplification of the 35 invention there is shown a control mechanism similar to that disclosed in my copending application, Serial Number 738,555, filed August 4, 1934, and in such control there is provided a circuit control box indicated diagrammatically by 40 the reference numeral 125 (see particularly Figure 1), to which current is supplied by feed lines 126—127. This box may be of any desired construction and is provided with circuit control devices 128, 129, 130, one to control the clutch for 45 the outer slide designated at O in Figure 7, one to control the clutch for the inner slide, designated by the letter I in Figure 7, and one to control the clutch for the lower slide designated by the letter L in Figure 7.

50 55 The numeral 131 in Figure 7, indicates diagrammatically a motor for controlling the operation of the press and which is connected to the feed lines by means of conductors 132—133, a switch or cut out device 134 being provided in one of the connections for the purpose of rendering the motor active or inactive at will.

60 Secured to a shaft 135 (see particularly Figure 1) which is mounted preferably in bearings in a bracket 136 are discs or rotatable elements 137— 60 138—139, one for each of the control devices, and as the construction and operation of each of these devices 137—138—139 is the same, the description of one will apply to them all.

65 The element 137 is provided on opposite faces with grooves or channels 140 opening through the faces thereof having enlarged portions 141. Slides 142 fit within the grooves or channels and are provided with extensions 143 which are preferably threaded. These extensions each pass 70 through a finger 144 preferably provided with a pointed end 145, and a fastening nut or collar 146 is threaded on the portion 143 so as to clamp the finger 144 as well as the slide 142. The finger 144 is adapted to be moved from the position shown in 75

full lines to the position shown in dotted lines in Figure 8, by loosening another collar 146.

With this arrangement it will be manifest that when the fingers are moved to the position shown in full lines in Figure 8, and secured in that position, they will be in an active position to project beyond the periphery of the element 137, but when it is desired to render the fingers inactive, the fastening nut 146 is loosened and the finger 144 turned to the dotted line position and then secured in this position.

Co-operating with the respective elements 137-138-139 are tappet wheels 147 rotatably supported by a shaft 148 journaled in suitable bearings 149. One of these tappet wheels 147 is provided for each of the elements 137-138-139, and each is provided with fingers 144 arranged on opposite faces of the respective elements 137-138-139. When these tappet wheels 147 are rotated by engagement of the tappets or fingers 144, a step by step movement will be imparted to the element 147, and the rotation of these elements will cause the switches (not shown) to be actuated to establish or interrupt the circuit or current 25 through the switch box to the respective electro-responsive devices 114.

This operation will be caused by the fingers of one face of the elements 137-138-139, and the elements 147 will be operated by the fingers on the other face of such element to re-establish or interrupt the circuit through the electro-responsive devices, so that during the operation of the elements 137-138-139, one set of fingers will open the circuit, and one set of fingers will close it.

Obviously, therefore, by arranging the tappets or fingers 144 with respect to each other, the circuits to the various electro-responsive devices may be readily controlled.

It will also be manifest that by setting the fingers 144, the slides 16, 46 and 74 may be controlled in their operation so as to render any one or more of the slides inactive to cause them to operate upon the work simultaneously, to cause them to operate upon the work successively, or to cause some of the slides to be rendered active, while others remain inactive, or to change the relative operation of one with respect to the other, all according to a predetermined selection by the operator.

Any suitable means may be provided for rotating the elements 137, 138 and 139, but a simple and efficient means embodies a sprocket chain 150 (see Figure 1) which passes over a sprocket wheel 135 on the shaft 135 and also over a sprocket wheel 151 connected to a shaft 152 of a speed reducing mechanism indicated diagrammatically by the reference numeral 153.

Another sprocket 154 constitutes a portion of the speed reducing mechanism (not shown but which may be of the ordinary well known construction), and over this sprocket 154 a sprocket chain 155 passes. This sprocket chain 155 also passes over the sprocket 119 (see also Figure 6) carried by the clutch element 73, (and which clutch element is freely rotatable about the shaft 67, when the co-operating clutch element is rendered inactive, in a manner to be set forth) so that when the shaft 67 is rotated, motion will be imparted to the sprocket chains 155-150 to rotate the shaft 135 and with it the elements 137-138-139.

It is thought that the operation of this portion of the mechanism will be clearly understood from the foregoing, but briefly stated it is as follows.

The respective slides 16, 46 and 74 are actuated

by means of their respective operating mechanisms, and the operation of the actuating mechanisms is controlled by the respective clutch devices, so that by controlling the clutch devices it will be possible to control or selectively render active or inactive predetermined ones of the slides, thereby placing in the control of the operator a means whereby any one or more of the slides may be rendered active. As before stated, the slides may be caused to operate either simultaneously upon the work, on opposite sides thereof, successively, or some of the slides may be rendered inactive, and the relative operation of the slides upon the work with respect to each other may also be controlled or varied.

At the same time the period of dwell of the dies upon the work may be controlled or varied, and the length or period of dwell of the dies carried by the respective slides upon the work and with relation to each other may also be varied. This is 20 accomplished by setting the fingers or tappets 144 upon the respective elements 137-138-139, according to the desire of the operator and of the work to be performed.

The mechanism, after the fingers or tappets 25 have been set, is automatic in operation, and the operation of each of the slides may be automatically commenced and stopped at any time in the cycle of operation of the press or at any point within the 360° of rotation of the driving or actuating eccentrics of the respective slides.

After the tappet fingers 144 have been set and the switch 134 closed, the circuit will flow through the respective electro-responsive devices O, I and L in Figure 4. For controlling the outer slide, the current will flow from the conductor 126, through the conductor 157, electro-responsive device 114O, conductor 158, switch device 159, conductor 160 back to the conductor 127. Similarly, when the inner slide is to be rendered active, current will flow from the conductor 126, through the conductor 161, electro-responsive device 114I, conductor 162, through the switch box 163, out of the switch box, through the conductor 164, back to the conductor 127, and likewise, when the 45 lower slide is to be rendered active, the current will flow from the conductor 126, through the conductor 165, electro-responsive device 114L, conductor 166, switch box 167, out through conductor 168, back to the conductor 127.

Thus, it will be manifest that the current may be caused to flow through either one or more of the electro-responsive devices O, I and L, and by the control of flow of the current through these devices, the operation of the slides 16, 46 and 74 55 may be correspondingly controlled. Inasmuch as the operating mechanism for the upper slide is disposed within the upper crown, and the operating mechanism for the lower slide is disposed in the lower crown of the press, which latter is also 60 hollow, and as these crowns constitute lubricant receptacles, the operating mechanism will be immersed or submerged in the lubricant, thereby obviating the necessity of providing special lubricating ducts or channels leading to the respective 65 parts of the operating mechanism.

In the form of press shown in Figure 10, the lower slide 74 is operated by means of eccentrics 169-170 connected to shafts 171-172. Eccentric straps 173-174 respectively cooperate with the 70 eccentrics 169-170 and are connected by means of arms 175-176 to members 177-178, which are adjustably connected as at 179-180 to the slide 74. These members 177-178 respectively slide through guides 181-182 to maintain the slide 74 75

in proper position and to relieve the slide of lateral stress so as to prevent binding of the slide upon its upright guides.

One set of these eccentrics 169—170 are arranged at each side of the slide.

Connected respectively to the shafts 171—172 are gears 183—184, and with which gears pinion gears 185—186 respectively mesh. These pinion gears are secured respectively to shafts 187—188, 10 and to these shafts are respectively secured gears 189—190. The gears 189—190 intermesh so that when one of the gears 189—190 is rotated, the other gear will be simultaneously rotated, and these gears will in turn, through the medium of 15 the gears 185—186 respectively rotate the eccentrics 169—170.

The gear 189 is preferably rotated by means of the belt or chain 122 which passes over a pulley 191 secured to the shaft 187. The lower slide is 20 controlled in its movement by means of the electro-responsive devices 114L, in the same manner as the slide 14 in the form of the invention shown in Figure 1, is controlled.

It will therefore be manifest that with the 25 present invention each of the work forming or shaping slides is adapted to be controlled in its operation independently with respect to the operation of the others. It will also be manifest that there is provided controlling means with 30 mechanism adapted to be set so as to cause the operation of the slides to be varied with respect to each other at will. This will render it possible for the operator to cause any two or more of the 35 slides to operate simultaneously or independently with respect to each other, and it is also possible to selectively control the operation of each slide so that the period of dwell or time of operation with respect to the other slides may be altered or varied so that the operator may have absolute 40 control of the operation of the slides.

It is even possible in the present invention to 45 keep one or more of the slides inactive while the other slides remain active, without the necessity of changing any of the mechanisms of the press or dismantling any of the parts. The structure as disclosed in this application permits adjustment by the operator for the action or inaction of any of the slides at will, simultaneously, individually or selectively.

50 It is also important that the respective slides be arrested at the limit of their stroke at predetermined points in the cycle of operation of the press and to maintain this point of arrest or stopping of the slides the same in repeated operations of the slides.

55 By reason of inaccuracies which are caused by the stopping mechanism, such as slippage of the braking means, the overthrow of the driving eccentrics, or by reason of many other conditions, it has not been possible heretofore to accomplish this result, that is the accurate stopping of the slide at a predetermined point.

60 It sometimes happens that the stopping or braking mechanism will operate upon the slide to arrest its movement before it reaches the limit of its stroke or the overthrow of the eccentrics, or the momentum of the eccentrics or driving shafts and gears will cause the slide to be retracted or moved away from the work before its 65 movement is arrested, with the result that sometimes this will be disastrous to the work.

65 With the present invention and by the provision of the link connecting means between the slides and the eccentrics and gears which operates the 70 slides, the inaccuracies of the stopping or of the

arresting of the slide at the limit of its stroke is minimized, and any movement of the slide due to such overthrow of the operating mechanism or for other reasons will only be a small fraction of the up and down movement of the slide as compared with the movement of the driving means, and this small fraction of movement will not be sufficient to appreciably affect the gripping or holding action of the dies carried by the slide, upon the work.

10 This is clearly shown in Figures 3 to 5 of the drawings, which illustrate only one slide, but the operation is the same with all of the slides.

In Figure 3 the slide 16 is shown at the limit of its throw with the pivots 28, 32 and 34 between the link 33 and the slide and crank arms substantially in alinement, illustrating that the slide has been arrested at the limit of its movement and the stopping of the slide has been accurate.

15 In Figure 4, however, the position of the parts is shown in the event that there has been a slight overthrow of the eccentrics or the driving mechanisms. In this position it will be seen that the pivots 28, 32 and 34 are slightly out of alinement. This movement has not appreciably affected the up and down movement of the slide 16 at the limit of its stroke because when there is an overthrow, the bell crank levers will be 20 rocked about their pivots 28 and the links 33 by reason of their pivotal connections 32 with the bell crank lever and pivot 34 with the slide, will swing about the pivots 34 as well as about the pivots 32 for a sufficient distance to compensate such overthrow and this will not affect the 25 up and down movement of the slide to any appreciable extent, such movement under such conditions which may occur, being only a small fraction of its up and down movement, which is not sufficient to affect the gripping or holding 30 action of the die 17 carried by the slide, upon the work.

35 In Figure 5 the parts are shown in the position they will assume when the slide is being raised out of engagement with the work.

40 With this invention it will be manifest that there is not only provided means for selectively controlling the operation of the slides one with respect to the other, and of the variation of the movement of the slides with respect to each other, but there is also disclosed a means whereby the operator can control the operation of the slides, and the movement of the slides will be arrested at a predetermined point even at the 45 limit of its stroke, and this stopping will be 50 uniform and at the same point in the repeated 55 operations of the press.

55 Furthermore, the slide having a set throw, means are provided whereby overthrow of the driving mechanism with respect to the slide when the latter is at the limit of its throw, will not 60 appreciably affect the slide. That is, the slide after it has reached the limit of its throw will substantially remain at such point, even though the operating mechanism, the eccentrics, gears, 65 etc., continue to operate by momentum, causing an overthrow after it has been attempted to stop the mechanism, regardless of such overthrow.

70 This same result will be accomplished in the event that the slide is arrested in its movement before it reaches the limit of its throw, that is in case of an "underthrow" of the operating mechanism with respect to the slide and the work.

75 While the preferred forms of the invention have been herein shown and described, it is to

be understood that various changes may be made in the details of construction and in the combination and arrangement of the several parts, within the scope of the claims, without departing 5 from the spirit of this invention.

What is claimed as new is:—

1. In a press, a plurality of slides on one side of the bed, an eccentric supporting shaft, a plurality of sets of eccentrics rotatable about said 10 shaft, a pair of shafts parallel to and on opposite sides of the first said shaft, a plurality of sets of rocking members mounted to move upon the said pair of shafts, link connections between one of said slides and one of said sets of rocking members, link connections between the other of said slides and the other of said sets of rocking members, eccentric strap connections between one set of said eccentrics and one set of said rocking members, eccentric strap connections between 15 the other set of eccentrics and the other set of said rocking members, and means for rotating said eccentrics about the eccentric supporting shaft.
2. In a press, a plurality of slides on one side 20 of the bed, an eccentric supporting shaft, a plurality of sets of eccentrics rotatable about said shaft, a pair of shafts parallel to and on opposite sides of the first said shaft, a plurality of sets of rocking members mounted to move upon the said 25 pair of shafts, link connections between one of said slides and one of said sets of rocking members, link connections between the other of said slides and the other of said sets of rocking members, eccentric strap connections between one set 30 of said eccentrics and one set of said rocking members, eccentric strap connections between the other set of eccentrics and the other set of said rocking members, means for rotating said eccentrics about the eccentric supporting shaft, 35 and means for selectively and variably controlling the rotation of said eccentrics.
3. In a press, a plurality of slides on one side 40 of the bed, an eccentric supporting shaft, a plurality of sets of eccentrics rotatable about said shaft, a pair of shafts parallel to and on opposite sides of the first said shaft, a plurality of sets of rocking members mounted to move upon the said 45 pair of shafts, link connections between one of said slides and one of said sets of rocking members, link connections between the other of said slides and the other of said sets of rocking members, eccentric strap connections between one set 50 of said eccentrics and one set of said rocking members, eccentric strap connections between the other set of eccentrics and the other set of said rocking members, means for rotating said eccentrics about the eccentric supporting shaft, a slide on the other side of the bed, and means for reciprocating the last said slide.
4. In a press, a plurality of slides on one side of the bed, an eccentric supporting shaft, a plurality of sets of eccentrics rotatable about said 10 shaft, a pair of shafts parallel to and on opposite sides of the first said shaft, a plurality of sets of rocking members mounted to move upon the said pair of shafts, link connections between one of said slides and one of said sets of rocking members, link connections between the other of said slides and the other of said sets of rocking members, eccentric strap connections between one set of said eccentrics and one set of said rocking members, eccentric strap connections between 15 the other set of eccentrics and the other set of said rocking members, means for rotating said eccentrics about the eccentric supporting shaft, a slide on the other side of the bed, and means for reciprocating the last said slide.
5. In a press, a plurality of slides on one side of the bed, an eccentric supporting shaft, a plurality of sets of eccentrics rotatable about said 20 shaft, a pair of shafts parallel to and on opposite sides of the first said shaft, a plurality of sets of rocking members mounted to move upon the said pair of shafts, link connections between one of said slides and one of said sets of rocking members, link connections between the other of said slides and the other of said sets of rocking members, eccentric strap connections between one set of said eccentrics and one set of said rocking members, eccentric strap connections between 25 the other set of eccentrics and the other set of said rocking members, means for rotating said eccentrics about the eccentric supporting shaft, a slide on the other side of the bed, and means for reciprocating the last said slide, and means for selectively and variably controlling the operation of all of said slides.
6. In a press, a plurality of slides on one side of the bed, an eccentric supporting shaft, a plurality of sets of eccentrics rotatable about said 30 shaft, a pair of shafts parallel to and on opposite sides of the first said shaft, a plurality of sets of rocking members mounted to move upon the said pair of shafts, link connections between one of said slides and one of said sets of rocking members, link connections between the other of said slides and the other of said sets of rocking members, eccentric strap connections between one set of said eccentrics and one set of said rocking members, eccentric strap connections between 35 the other set of eccentrics and the other set of said rocking members, means for rotating said eccentrics about the eccentric supporting shaft, a slide on the other side of the bed, and means for reciprocating the last said slide, and means for selectively and variably controlling the operation of all of said slides, the reciprocating means for said slides embodying a common prime mover, and operative connections between said prime mover and each of the slide reciprocating means.

RUDOLPH W. GLASNER.
